ATTORNEYS

UNITED STATES PATENT OFFICE.

WILLIAM W. FOSS, OF GOODHART, MICHIGAN, ASSIGNOR OF ONE-HALF TO
SAMUEL W. BARKLEY, OF GOODHART, MICHIGAN.

SNOW-PLOW.

SPECIFICATION forming part of Letters Patent No. 710,853, dated October 7, 1902.

Application filed March 28, 1902. Serial No. 100,438. (No model.)

To all whom it may concern:

Be it known that I, WILLIAM W. FOSS, a citizen of the United States, and a resident of Goodhart, in the county of Emmet and State of Michigan, have invented a new and Improved Snow-Plow, of which the following is a full, clear, and exact description.

The object of the invention is to provide a new and improved snow-plow arranged for attachment to a road-machine and adapted to open up a road covered with snow, the plow being simple and durable in construction, very effective in operation, and arranged to easily move the snow sidewise without requiring much power to move the plow forward through the snow.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a longitudinal sectional elevation of the improvement on the line 1 1 of Fig. 2. Fig. 2 is a plan view of the same. Fig. 3 is a transverse section of the same on the line 3 3 of Fig. 1, and Fig. 4 is a like view of the same on the line 4 4 of Fig. 1.

The sides or blades A of the snow-plow are connected together at their forward ends by a hinge B to allow of swinging the blades into the desired angle relative one to the other to open up the road in a wider or narrower path, according to requirements. The forward ends of the blades A are connected by chains C with the supporting-beams D of a road-machine of any approved construction, and the said supporting-beams are also connected by brackets E with the blades A at the inside thereof and near their rear ends, as plainly indicated in Figs. 1 and 2.

The supporting-beams D of the road-machine can be raised or lowered in the usual manner and swung sidewise to cause the blades A to assume the proper position both as to the road-bed and the width of the path to be made by the snow-plow. The lower edges A' of the forward portions of the blades A are flared outwardly, as plainly indicated

in Fig. 3, and the rear ends A² of the blades are curved outwardly and are inclined in an upward and outward direction, as plainly indicated in Figs. 2 and 4.

The bottom edges of the ends A² are rounded off in an upward direction, as indicated at A³.

Now by the arrangement described the hinged or apex end of the snow-plow readily enters the snow, and as the blades A diverge rearwardly and then curve outwardly at their extreme rear ends it is evident that the snow is gradually pushed sidewise by both blades on moving the snow-plow through the snow, so that very little power is required for the forward movement of the plow to form a path of a desired width. By curving and inclining the rear ends of the blades, as described, the snow pushed sidewise is not liable to roll back and fall into the path made by the plow, and, furthermore, the banks of snow piled up sidewise are inclined, so that the snow will leave the path free and clear.

Having thus described my invention, I claim as new and desire to secure by Letters Patent—

1. A snow-plow, comprising a pair of longitudinal blades secured together by a hinge, a pair of chains connected with said blades for the purpose of flexibly connecting said blades to the frame of a road-machine, and a pair of brackets connected with said blades for the purpose of connecting said blades to the frame of said road-machine independently of the connection made by said chains.

2. A snow-plow, comprising a pair of longitudinal blades flexibly connected together, thereby forming a substantially V-shaped member, a pair of chains connected with said V-shaped member adjacent to the junction of said blades for the purpose of flexibly connecting said V-shaped member to the frame of a road-machine, and means for connecting said V-shaped member to said frame independently of the connection made by said chains.

In testimony whereof I have signed my name to this specification in the presence of two subscribing witnesses.

WILLIAM W. FOSS.
